(57) **CLAIM**

The ornamental design for a push-to-talk communication device having a gripping surface, as shown and described.

DESCRIPTION

FIG. 1 is a front perspective view showing my new design for a push-to-talk communication device having a gripping surface.

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines depict unclaimed portions of the push-to-talk communication device having raised buttons, which form no part of the claimed design.
